UNITED STATES PATENT OFFICE.

CHARLES B. STILWELL, OF PHILADELPHIA, PENNSYLVANIA, ASSIGNOR TO
THE UNION PAPER BAG MACHINE COMPANY, OF SAME PLACE.

PAPER-BAG MACHINERY.

SPECIFICATION forming part of Letters Patent No. 417,346, dated December 17, 1889.

Application filed August 2, 1889. Serial No. 319,550. (No model.)

To all whom it may concern:

Be it known that I, CHARLES B. STILWELL, of the city and county of Philadelphia, State of Pennsylvania, have invented a new and useful Improvement in Paper-Bag Machinery, of which the following is a true and exact description, reference being had to the accompanying drawings, which form a part of this specification.

10 My invention relates to the construction of machinery for making paper bags, and especially to machinery such as is shown and described in my patent, No. 407,794, dated July 30, 1889.

15 My object in devising the present improvements is chiefly to improve and increase the efficiency of the said machine.

My invention will be best understood after a description of the drawings, in which it is 20 illustrated, and in describing the said drawings, as well as more particularly in the claims, I will point out the various novel features of the machine.

Reference being now had to the drawings, 25 Figure 1 is a plan view of a paper-bag machine having my improvements; Fig. 2, a side elevation of the same; Fig. 3, a plan view of a portion of the mechanism for forming a bellow-folded tube and severing it into bag-blanks; Fig. 4, a side elevation of the same parts; Fig. 5, a cross-section through the former-plates on the line $x-x$ of Fig. 3, showing a part of my new adjustable device for sustaining the former-plates. Fig. 6 is a cross-section on the line $y-y$ of Fig. 3. Fig. 7 is a front view of the mechanism for slitting the bellow-folded tube longitudinally; Fig. 8, a side view of the same; Fig. 9, a view showing the construction of the knife-blades; Fig. 10, 30 a plan view of the tube after it has been slit; Fig. 11, a section of said tube on the line $z-z$ of Fig. 10. Fig. 12 is a side elevation showing my new device for forming a slack in the tube at the time a blank is cut from it, Fig. 45 13 showing the parts in a different position. Fig. 14 is a plan view of the roll over which the bag-blank is fed and on and by means of which a portion of the operation of opening the bottom of the blank into the diamond form is carried on, said view showing also the mechanism immediately connected with said

roll. Fig. 15 is an end view of the same; Fig. 16, a view of the roll, showing its central cavity and gripping-finger. Fig. 17 is a central cross-section through the roll; Fig. 18, an end view showing the mechanism for actuating the central gripping-finger of the roll. Fig. 19 is a view in direction about perpendicular to a plane passing through the axes of shafts I' and G^2 ; Fig. 22, of a portion of the front end of the machine, showing the aligning-fingers which cause the upper ply of the blank to remain in proper position to receive the distending fingers. Fig. 20 is a perspective view illustrating the relative action of the aligning and distending fingers; Fig. 21, a plan view of the aligning-finger and the cam which actuates it. Fig. 22 is a front view of the roll I ; Fig. 23, a side elevation of the distending apparatus at the end of the machine; Fig. 24, a perspective view of the end of one of the distending-fingers; Fig. 25, perspective views of the spring and end plate attached to said finger, and Fig. 26 is a detail hereinafter referred to.

A is the frame of the machine, the general character of which (the machine) is similar to that shown in my former patent aforesaid, and as shown in Figs. 1 and 2 of the drawings.

In the present application I have not illustrated the mechanism for forming the final folds of the bottom, but only that which forms the blanks and opens their bottoms into what is called the "diamond fold."

B is the roll of paper; B' , a paste-trough; B^2 , the paste-roller; B^3 and B^4 , guide-rolls, and C the standard to which the former-plates $C' C^2$ are attached.

c are guide-fingers; $C^5 C^6$, guide-rolls working with their edges between former-plates $C' C^2$.

C'' is a wedge extending between plates $C' C^2$ and uniting them together.

All the above parts are of well-known construction and need not be particularly described.

To the top of the upper former-plate C^2 , I secure a clip C^3 with a slot in its free end, and to the frame A, I secure by a bolt c' , passing through a slot therein, a clip C^4 , which is again secured to the clip C^3 by a bolt c^2 , passing

through the slot in said clip. The function of the two clips is to support the former-plates and enable them to be adjusted and aligned from time to time, for in making the 5 bellows-sided square-bottomed bags for which my apparatus is especially intended the utmost nicety of alignment is necessary to insure perfect work, and to that end I have devised the adjustable clips C³ and C⁴. A short 10 distance back of clip C³ the upper former-plate C² terminates, and near its end I form longitudinal slits c³ c³, below which are corresponding slits c in the lower plate C', and to revolving shafts D D', above and below the 15 former, are secured, by means of adjustable holders D², knife-blades D¹.

D³ D³, &c., represent set-screws for adjusting the knife-holders on the shafts, and D⁵ D⁵, &c., set-screws for adjusting the slotted 20 knife-blades D⁴ on the holders. The speed of shafts D D' is similar and such that the knife-blades revolve once for every bag-blank length working through the slits c³ and c⁴ in the former-plates, and the bottom ones being set so as to cut slightly in advance 25 of those on top, so as to slit the paper, as shown in Figs. 10 and 11. This device for cutting the paper forms one of the novel features of the machine.

30 C⁶ C⁶ and C⁷ C⁷ are guide-rolls for heading and aligning the tucked tube, and as they form in themselves no part of the present invention they need not be particularly described. In front of the rolls C', I secure 35 upon the lower former C' a plate C⁸, (see Figs. 3, 4, and 6,) forming an additional aligning-guide, which, co-acting with the guide-rolls C⁶ and C⁷, I have found to greatly aid in keeping the tube straight and free from side 40 strains, which would cause it to fold badly in forming the bottom. The tucked sides of the tube pass beneath the edges of this plate and the upper ply over it.

45 C⁹ C⁹ are feed-rolls, and on the end of the former-plate C' is a knife E, for cutting the lower side of the tube, while above knife E is another knife E', which acts to cut the sides and top of the tube and complete the severing of the blank.

50 E² is a revolving striker, which coacts with the knife-blades E E' to sever the paper in the usual manner, the striker being attached to a wheel E³, set on an oblique shaft E⁴.

55 In using a striker and stationary knives to sever the blanks it is advantageous to have a slack in the paper against which the striker presses, so that it will be free to bend up on the edges of the knives. My new device for effecting this slack in the paper is shown in 60 Figs. 12 and 13. In the space which intervenes between the knife-edges E E' and the rolls G G', which feed the blanks forward, I interpose an arm or arms F, pivoted on a shaft F', and having at their other ends a plate F³, which should be slightly curved 65 downward, as shown. Upon revolving shafts F⁴ and F⁵, above and below arms F, I secure

70 hubs F⁶, from which project roll-segments F⁷, which, as the shafts revolve, meet and grip the paper, as shown in Fig. 13. The normal line of the web being below the plane on which the segments meet, the tube is raised upon the lower segment, as shown. On the shaft F⁴ is secured a cam F¹⁰, which presses 75 against the arms F or an attachment thereto 80—such as the wiper F²—which, as shown, has a number of faces f, which can be turned up in turn to act on the face of cam F¹⁰. A spring F⁹, acting on a heel F⁸ of arms F, keeps 85 them in contact with the cam F¹⁰, which is so formed and set as to hold the plate F³ in the position shown in Fig. 12 until after the roll-segments F⁷ have gripped the tube, as shown in Fig. 13, when the plate is allowed to rise, as shown, thus forming a slack in the paper 90 just before it is struck by the striker E².

95 G' and G² (see Figs. 14 to 18, and Fig. 23) are feeding-rolls through which the severed blanks are fed to the mechanism which opens their bottoms. On the lower roll G, or on 100 parts g, secured to the same shaft G², are the gripping-fingers g', pivoted at g² and having cam-rolls g³ working against cams II, which cause the fingers to clamp the edges of the paper on the rolls and release it at proper 105 times, as described in my former application. In the center of roller G, I form a recess g⁴, and from its lower part I form a longitudinal perforation g⁵ to receive a shaft g⁶, to which a gripping-finger g⁷ is attached. The portion 110 of the roll-face on which finger g⁷ presses is preferably flattened, as shown at g¹⁰. The shaft g⁶ extends beyond the end of roll G and has on its end a crank-like cam-wiper g⁸ g⁹, the pin g⁹ of which rests against a stationary 115 cam II', which, as the roll revolves, causes the shaft g⁶ to turn so as to alternately clasp the finger g⁷ down on the roll and cause it to move up from it. The function of this centrally-located gripping-finger is to clamp the 120 front edge of the bottom ply of the blank against the lower roll G and cause it to move down with it (said roll) while the fingers g' and distending-fingers L are, with their co-acting mechanisms, opening the blank on the 125 plane of the bag-bottom to be formed on it, the lower ply being thus drawn down inside the guide-plate O' and delivered to the rolls N N' in correct position.

130 The use of a central gripping-finger was mentioned and illustrated in my former application as an alternative to the device particularly described and claimed there, but which, as will be seen, is not applicable to my improved machine.

135 After issuing from between the rolls G G' the top ply of the blank is gripped between the roll I and the narrow roll J, which last roll is freely journaled and supported on a spring J⁵, its journal J' being attached to the spring 140 through connections J² and J⁴. The roller I, which coacts with roll J, is in my present construction made up of two rims i i, cut away at i' i' and fastened to the positively-driven

shaft I' and a loosely-journalized ring i², of less diameter than the thicker portion of rims i, but of greater diameter than the recessed portions i'. The roll I is set so that when the 5 edge of the blank is presented to it it is gripped between rims i and the narrow roll J and drawn forward to the full extent desired. Then when the upper ply of the paper is drawn backward from roll J the roll I has turned so 10 that the recessed portion i' of the roll is opposite roll J, and the paper is thus released from the grip of rims i, and is held between roll J and the loose ring i², so that it meets with only a slight frictional resistance to its 15 backward motion.

It will be noticed that in this machine I secure the guide-plate O' to the support J⁴, which is fastened to spring J⁵. This mode of securing the guide-plate I have found to give 20 good results, as giving the plate some power of yielding to under pressure.

The distending-fingers L L are, as shown, substantially similar in principle to those shown in my former patent. They are secured to tubes L³, resting on rods L², which are secured by a clamp L⁵ to a rock-shaft L⁶. Springs l⁴ tend to keep the points of the fingers pressed together, and cams H⁴, acting on cam-rollers L', attached to fingers L, cause 30 them to diverge at proper intervals, an arm L⁷, resting against a cam H⁵, (see Fig. 2,) causing the rock-shaft to move to give the necessary upward motion to the fingers. The spring l⁴ is fastened at one end to pin l³ on an adjustable clamp L⁴, which is secured to rod L³ 35 by a set-screw l². The other end of the spring is attached to tube L². (See Fig. 26.)

The special construction shown is novel and an improvement on the arrangement shown 40 in my former patent; and another important improvement in this part of the apparatus consists in making the ends of fingers L elastic, which I accomplish by connecting a steel plate l' with the rigid end of the fingers by 45 a spring, such as is shown at l, Figs. 24 and 25.

When the machine is running at high speed, it is important that the distending-fingers should strike the corners of the upper 50 ply of the tube as nearly in the spot where the corners of the bag-bottom are to be formed as possible, and to facilitate this I have devised the mechanism shown in Figs. 19 to 55 21. To the frame of the machine I attach pivots M', on which are secured blocks M², and in these blocks are secured fingers M by means of set-screws m, by which they can be 60 adjusted and secured. Springs m' serve to press the fingers inward, as shown, and wipers on the backs of blocks M² bear against cams H³, which, as shown, are secured to the shaft 65 I', but which of course could have independent connections. The fingers are so placed and the cams H³ so set that the fingers (which I will hereinafter refer to as "aligning-fingers") normally rest outside of the path of the blank, but just before the distending-fingers L are operated the aligning-fingers are

thrown quickly upward, so as to tightly press upward beneath the corners of the upper ply and upper inwardly-folded part of the side 70 of the blank, thus counteracting any tendency to sag, and insuring that when the fingers L come in contact with the corners they (the corners) will be in the correct line and position. 75

Referring next to the feed-rolls N N', through which the blanks first pass after having had their bottoms distended into the diamond form, I have found it advantageous not to engage the front end of the blank so as to 80 draw upon it much in front of the first cross-fold in the paper, and I have accordingly recessed the presser-wheel N, as shown at n, and driven this wheel by positive connections, as shown at n⁵, n⁶, and n⁷, the recess of course 85 being so that as to clear that portion of the blank upon which it is not desirable to pull, while at the proper moment the blank is seized between the extended face of roll N and roll N'. Roll N is journaled at n' in a 90 sliding block n², moving in guides n³ and impelled forward by a spring n⁴, a stop n⁵ being provided which permits the spring to force the extended periphery of roll N against roll N', but does not permit any contact between 95 the recessed portion of the roll N and roll N'.

The operation of my improved machine is, except in some minor details, the same as described in my former patent, granted July 30, 1889. The web of paper is wound on the 100 roll B, thence passes over roll B³ and under roll B⁴, the paste-roller B² applying a line of paste to one edge as it passes upward. From roller B⁴ the web passes beneath former-plate C' and is folded down upon it and tucked 105 between the plates C' and C² by fingers c and wheels C⁵. One edge of the paper is folded down on the upper former-plate, passing beneath the clips C⁴ and C³, while the other pasted edge lies over clip C³. Any convenient device for pressing the pasted seam may 110 be used. The revolving shafts E and D' cause the cutters to revolve once for every bag-blank length of tube passing between them, and the knives D⁴ slit the top and bottom plies of the paper, as shown in Figs. 10 and 11. The tube then passes between guide-wheels C⁶ C⁶ and C⁷ C⁷ and its upper ply over plate C⁸, which is of the same breadth as the former-plate C² and may be considered, together with the guide-wheels, as a continuation of it, and from the plate C⁸ it passes with 120 the paper accurately aligned and unstrained to the end of the former C', whereon a knife-blade E is secured, with a blade E' secured 125 above it, as shown. Passing by the knife-blades the end of the tube passes beneath the plate F³ and between the shafts F⁴ and F⁵, the revolving roll-segments of which grip it and move it forward, in doing so raising the 130 tube above the plane drawn from the knife-blades to the plate F³ in its downward position. The cam F¹⁰ then permits the plate F³ to rise, leaving a slack between the end of

the knives and the gripping-segments, and the striker E² then comes in contact with the paper and severs the tube against the knife-edges.

- 5 With the exception of the device for supporting the formers, the slitting mechanism, the use of the plate C⁸, and the device for forming a slack in the tube the foregoing parts of the machine are all of a well-known kind.
- 10 It will be obvious that the particular kind of knives used to coact with the striker in severing the blank is not material, any of the known combinations of one or more knives and a striker being of course equally adapted for use with my device for forming a slack in the tube prior to the action of the striker upon it. It will also be obvious that the plate F³ may normally lie below the line of the paper between the end of the former and the 15 rolls G G', in which case the segments F³ may meet on said line instead of above it, as shown, the action in forming a slack being the same when the plate F³ rises. The severed tubes next pass between the rolls G G', 20 the central gripping-finger g⁷ grasping its front lower edge and pulling it down as the rolls revolve, while the upper edge passes out over the narrow supporting-roll J and is gripped and drawn forward by the rims 25 i. The gripping-fingers g⁴ are operated so as to engage the corners of the lower plies of the blank and clamp them against roll G in the line on which the bag-bottom is to be formed, and the cams actuating the rock-shaft L⁶ and the fingers L are so set as to cause the 30 said distending-fingers to press upward and outward, so as to engage the opposite corners of the upper plies of the blank and coact with the fingers g⁴ in opening the blank out 35 square on the plane of the bag-bottom. Just before the fingers L engage the blank the aligning-fingers M are thrown up, so as to insure the upper corners of the blank being in the plane in which the fingers L are arranged 40 to engage them. This device and the additional device of making the operative ends of the distending-fingers elastic greatly increases the accuracy of operations. When 45 the top of the blank has been pushed forward over the roll J for a certain distance, the tucker P comes down upon it and draws it backward from said roll, and at the point in the motion of the machine where this occurs the recesses i' in rims i cause them to 50 release their grip on the paper, which is then clamped between roll J and the loose sleeve i², which permits it to be readily drawn back notwithstanding the continuous motion of shaft I' in the opposite direction.
- 55 The tucker P and its actuating mechanism is shown in Figs. 1 and 2 of the drawings and does not differ substantially from the similar mechanism described in my former patent. The tucker slides in fixed guides P', fixed adjustably to the frame at P². A link p connects the tucker to a lever-arm p', attached to a shaft p², said shaft being actuated by a

lever-arm p³, to which is connected a rod p⁴, the end of which rests against an actuating-cam H². A spring p⁶ serves to keep the tucker 7c normally in its uppermost position. As these parts do not, as aforesaid, differ materially from those described in my former patent, it is not necessary to show them in detail. As the partially-opened blank passes downward, its 75 lower end passes between the rolls N and N', the recess n in roll N being set so that the end of the blank is not gripped between the rolls until a point is reached just in front of the transverse fold made by tucker P when the 80 blank is gripped and drawn forward between said rolls N and N'.

The remaining parts of the machine I have not illustrated, as they form no part of my present invention, and are or may be the same 85 as shown and described in my former patent, upon which my present case is an improvement.

Having now described my invention, what I claim as new, and desire to secure by Letters 90 Patent, is—

1. In a bag-machine, the combination of the former-plates C' C², with a clip C³ secured to the top former-plate, and the supporting-clip C⁴, attached to the base of the machine and 95 adjustably connected with clip C³, substantially as and for the purpose specified.

2. In a bag-machine, the combination of the former-plates C' C², with a clip C³ secured to the top former-plate, and the supporting-clip 100 C⁴, adjustably attached to the base of the machine and adjustably connected with clip C³, substantially as and for the purpose specified.

3. In a bag-machine, the lower former-plate C', having a shorter upper former-plate C² secured over it, in combination with a short 105 supplemental former-plate C⁸, attached to the lower plate, and aligning-guides situated above the lower former, between the end of plate C² and plate C⁸, all substantially as and 110 for the purpose specified.

4. In a bag-machine, the former-plates C' C², having parallel corresponding slits c³ c⁴ and c¹ c² formed in them, in combination with revolving slitting-knives secured in pairs on 115 shafts situated above and below the former-plates and so arranged as to enter the slits in the plates as they revolve, substantially as and for the purpose specified.

5. In a bag-machine, the combination of 120 mechanism for forming a bellows-folded tube, a striker, and one or more knives for severing the tube into bag-blanks, of revolving roll-segments arranged to grasp the tube at intervals, a presser-plate acting on the tube between the striker and roll-segments, and cam mechanism, as described, whereby said plate is made to rest on the paper below the contact-plane of the roll-segments before the paper is gripped by them and move upward, 125 leaving a slack in the paper after it is gripped, all substantially as and for the purpose specified.

6. In a bag-machine having mechanism for

5 folding a bellows-sided tube and severing it into bag-blanks, and rolls G G', whereby the blanks are fed to mechanism for opening the bottom of the blanks, the combination of fingers arranged to engage the upper corners of the blank on the line of the bag-bottom to be formed with the under roll G, having fingers acting to engage the lower corners of the blank on the line of the bag-bottom to be formed, 10 and a central gripping-finger g^7 , arranged to clamp the advancing lower edge of the blank centrally and draw it down as the roll revolves.

15 7. In a bag-machine substantially as specified, the combination of a narrow supporting-roller J, with a roll I, having recessed rims i^2 and a central loosely-journalized ring i^2 .

8. In a bag-machine substantially as specified, the combination, with the distending-fingers L L', of spring-supported terminal plates l^7 .

9. In a bag-machine substantially as specified, the combination, with the rock-shaft L^6 , of rods L^3 , secured to said shaft, tubes L^2 , journaled on said rods, springs l^4 , acting to turn the tubes inward, distending-fingers L, secured to tubes L^2 , cam-rolls L', attached to fingers L, and cams acting on said cam-rolls, all substantially as and for the purpose specified. 20

10. In a bag-machine substantially as specified, the combination, with the distending-fingers L, of the aligning-fingers M, and cam-mechanism, as specified, whereby said aligning-fingers are made to press up the upper corners of the blank as the distending-fingers engage them. 25

CHARLES B. STILWELL.
